UNITED STATES PATENT OFFICE.

JOHN F. MARCUM AND GODFREY HAUENSTEIN, OF OLDS, IOWA.

GATE-FASTENER.

SPECIFICATION forming part of Letters Patent No. 626,180, dated May 30, 1899.

Application filed February 24, 1899. Serial No. 706,697. (No model.)

To all whom it may concern:

Be it known that we, JOHN F. MARCUM and GODFREY HAUENSTEIN, of Olds, in the county of Henry and State of Iowa, have invented a new and Improved Gate-Fastener, of which the following is a full, clear, and exact description.

This invention relates to improvements in fastening devices for swinging gates, and the object is to provide a simple and comparatively inexpensive fastening device that will be automatically moved to its locking position by the gate swinging closed from either direction.

15 We will describe a gate-fastener embodying our invention and then point out the novel features in the appended claims.

Reference is to be had to the accompanying drawings, forming a part of this specification, 20 in which similar characters of reference indicate corresponding parts in all the figures.

Figure 1 is a perspective view of a gate, showing a fastener embodying our invention as applied thereto. Fig. 2 is a section on the 25 line 2 2 of Fig. 3. Fig. 3 is a top plan view showing the fastener in its locking position. Fig. 4 is a plan view showing the device in its releasing position. Fig. 5 is a section on the line 5 5 of Fig. 2.

30 Referring to the drawings, 1 designates a gate having hinge connection with the gate-post 2. Mounted to swing on the other gate-post 3 is a locking yoke or latch consisting of divergent plates or members 4 5, which are 35 attached to a rock-bar 6, mounted to rock in eyes 7, attached to the inner face of the post 3. Attached to the upper end of the post 3 is a segment-rack 8, provided at its central portion with a notch 9, and the top edge of 40 this plate is inclined downward and outward to end stops 10 on the ends of the plate. Pivotally connected to the upper end of the rod 6 is a latch-lever 11, adapted to engage in the notch 9 to hold the yoke in its locking position.

45 In operation when it is desired to open the gate the lever 11 is swung upward to clear it from the notch 9. Then by pushing the gate in either direction the yoke, consisting of the 50 members 4 5, will be swung substantially to the position shown in Fig. 4, releasing the

gate. At this time the lever 11 will engage with one of the stops 10. When it is desired to close the gate, it is to be swung to its closing position, and in so doing it will engage with 55 the locking-yoke and automatically swing it to its locking position and move the lever 11 into the notch 9, as indicated in Fig. 3.

By inclining the upper edge of the plate 8 as shown and described the locking-yoke will 60 be prevented from being swung to its closed position by force of wind or other slight pressure, because the lever 11 will engage frictionally upon the inclined surface or edge.

Having thus fully described our invention, 65 we claim as new and desire to secure by Letters Patent—

1. A gate-fastener, comprising a yoke having divergent members and adapted for swinging connection with a post of the gate, a 70 swinging lever having connection with the yoke, and a notched plate for receiving said lever, substantially as specified.

2. A gate-fastener, comprising a yoke having divergent members, a rod adapted for 75 swinging connection with a gate-post and upon which said yoke is mounted, a lever having pivotal connection with the upper end of said rod, and a plate secured to the gate-post and having a notch to receive the lever, 80 substantially as specified.

3. A gate-fastener, comprising a yoke having divergent members, a rod on which the yoke is mounted, the said rod being adapted for swinging connection with a post of the 85 gate, a lever pivoted to the upper end of said rod, and a segmental plate to be secured to the upper end of the post, the said segmental plate having a notch at its central portion and stops at its ends, the edge of the plate 90 between the stops and the notch being inclined, substantially as specified.

4. A gate-fastener, comprising a rock-bar with arms thereon, a swinging latch in connection with the bar and a member coacting 95 with the latch to engage the same and hold the rock-bar.

JOHN F. MARCUM.

GODFREY HAUENSTEIN.
